UNITED STATES PATENT OFFICE.

PETER PARKE, OF CHICAGO, ILLINOIS, ASSIGNOR TO PRESSED STEEL CAR COMPANY, OF PITTSBURGH, PENNSYLVANIA, A CORPORATION OF NEW JERSEY.

CENTER-SILL CONSTRUCTION.

1,115,861.

Specification of Letters Patent.

Patented Nov. 3, 1914.

Application filed December 26, 1911. Serial No. 667,573.

To all whom it may concern:

Be it known that I, PETER PARKE, a citizen of the United States, residing at No. 5706 Peoria street, Chicago, in the county of 5 Cook and State of Illinois, have invented certain new and useful Improvements in Center-Sill Construction, of which the following is a full, clear, and exact description of the invention, such as will enable others 10 skilled in the art to which it appertains to make and use the same, reference being had to the accompanying drawings, forming part of this specification.

A great many old wooden cars of light 15 weight and comparatively small capacity still remain in use on many of the railroads throughout the country; and these cars of necessity commingle with modern cars of great weight and large capacity. Hence in 20 the handling and transportation of freight trains composed of cars greatly varying in size and strength, the smaller capacity cars are subject to buffing and pulling shocks and other strains of a severity far beyond what 25 such cars were ever designed to stand. Moreover, light capacity cars are frequently overloaded far beyond their rated or originally intended capacity, and there is an increased tendency to overload the smaller 30 capacity cars because of the increasing number of large capacity cars. The general result is that the old or light capacity cars are becoming less and less equal to the increased strains to which they are subjected and more 35 and more of them collapse in service or are otherwise impaired and broken up in such a manner as to be beyond repair. My invention is intended to overcome this condition and to equip the old cars to meet the 40 increased stresses to which they are now subjected, and at the same time to adapt many of them so as to be capable of carrying a considerably increased load.

My invention relates to a new and useful 45 improvement in underframes for railway cars, and particularly to an underframe made of metal which can be readily applied to wooden cars for the purpose of repairing and rebuilding the same, an object being to construct an underframe wherein the 50 center sill is preferably in the form of a double member, the ends of said center sill being spliced and connected to members which form extensions thereof and constitute 55 the draft sills of the car, the outer ends of

said draft sills being connected by members serving the functions of end sill and striking plate.

Another object of my invention is to provide means whereby the center sills are 60 trussed to increase their load carrying capacity, provision being made for the anchoring or securing of the ends of the truss rods in brackets which are secured to the draft sills, thus relieving the wooden end sill of 65 the severe strains due to the tensional strains in the truss rods, and providing a more secure anchorage for the ends of the truss rods than the wooden end sill would afford.

Other features of my invention reside in 70 the construction, arrangement and combination of the several parts, as will hereinafter be described and afterward pointed out in the claims, it being understood that changes in the form, proportion, size and minor 75 details may be made within the scope of the claims, without departing from the spirit or sacrificing any of the advantages of my invention.

In the drawings, in which similar refer- 80 ence characters refer to similar parts throughout the several views, Figure 1 is a plan view of part of an underframe constructed in accordance with my invention. Fig. 2 is a side elevation of the center con- 85 struction of part of the underframe, the bolster being shown in section taken at line 2-2 of Fig. 1, the end sill, side sills and intermediate sills being removed. Fig. 3 is a part longitudinal section on line 3-3 of 90 Fig. 1, and Fig. 4 is an end elevation of the underframe of the car.

Referring now in detail to the drawings, 1, 1 indicates the center sills of the underframe which, for the purpose of illustration, are shown as rolled channel beams, the outer ends 2, 2 of the center sills extending beyond the bolster 3 and to said outer ends 2, 2 draft sills 4, 4 of Z or any other preferred section and preferably deeper than 100 the center sills are secured. The ends 5, 5 of these draft sills lap past and are secured to the webs 6, 6 of the center sills. To the upper flanges 7, 7 of the draft sills and upper flanges 8, 8 of the center sills, a tie plate 9 of 105 substantially octagonal or other suitable shape is secured, such tie plate extending along the top of the center and draft sills for some distance from the center line of the bolster. To the lower flanges 10, 10 of the 110

draft sills and lower flanges 11, 11 of the center sills, a tie plate 12 of similar shape is secured, said tie plate resting upon and being also secured to the top member 13 of the body bolster.

At a point near to the outer ends of the draft sills and on the outer side thereof are secured bracket members 14, 14, each having a vertical portion 15 adapted to contact with and be secured to the web 16, 16 of the draft sills 4, 4 and a horizontal or flanged portion 17 adapted to rest upon and be secured to the lower flanges 10, 10 of the draft sills 4, 4. This bracket member is further provided at its end with a portion 18 extending at substantially right angles to the portions last mentioned, and also with an aperture 19 through which the end 20 of the truss rod may be passed.

21, 21 indicate the center sill truss rods which pass over the truss rod supports 22 secured to the web of the center sill and resting upon the upper side of the tie plate 12, and extend from such support along-side the draft sills 4, 4 and through the apertures 19, 19 of the bracket members 14, 14 above referred to. The ends of the truss rods are secured and retained in such apertures 19, 19 by any suitable means, such as a screw thread and nut 23 as shown in the drawings. It will be noted, as shown in Fig. 1 of the drawings, that the forward draft lugs 24, that is the draft lugs that resist the pulling strains transmitted to the draft gear (not shown) are secured to the draft sills at substantially the same points as those at which the bracket members 14 are secured to the draft sills, thus insuring that the truss rods 21 will take their share of the strains transmitted through the center sills by the draft gear.

25 indicates the end sill of the underframe which is notched at 26 to permit the end portions of the draft sills to pass therethrough, the notched out portion of the end sill resting upon the top flanges 7, 7 of the draft sills. The end sill is secured to the draft sill by bolts 27, which pass through the end sills in a substantially vertical direction and through holes 28, in the lower flange 17 of the bracket member 14, a filler 29 being interposed when necessary. The end portions of the draft sills extending beyond the outer vertical face of the end sill have a portion 30 of their top flanges 7 split, and bent over in a direction opposite to that of the main portion of the flange, relative to the web of the draft sill, to form a shelf or support for the upper portion 31 of the striking member 32.

The striking member 32 is adapted to fit in the space between the ends of the draft sills, an aperture 33 being provided for the coupler shank to pass through, and is further provided with a portion 34, which ex-

tends over and is supported by the flanges 30 of the draft sills. The portion 34 is shown as being of T section, but may be made of any other suitable form to meet the existing conditions, and is secured to the flanges 30 of the draft sills, and also to the upper horizontal flange 35 of the bracket member 14. 40 indicates the dead wood of the wooden striking member which rests upon the top portion 34 of the metallic striking member 32, and is secured thereto by bolts 36 which pass in a substantially vertical direction through the dead wood and striking member, and also support the carry iron 37.

38 indicates the wooden side sills and 39 the intermediate sills of the underframe which are of the usual construction.

Having thus described my invention, what I claim as new and desire to secure by Letters Patent is:—

1. In a car underframe, a channel shaped center sill and a draft sill, in combination with a draft lug, truss rod anchor member and striking member, all secured to said draft sill.

2. In a car underframe, a channel shaped center sill and a draft sill of greater depth than said center sill, in combination with a draft lug, truss rod anchor member and striking member, all secured to said draft sill.

3. In a car underframe, a channel shaped center sill and a draft sill secured to said center sill outside the body bolster, in combination with a draft lug, truss rod anchor member and striking member, all secured to said draft sill.

4. In a car underframe, a channel shaped center sill and a draft sill secured to said center sill outside the body bolster, said draft sill being of greater depth than said center sill, in combination with a draft lug, truss rod anchor member and striking member, all secured to said draft sill.

5. In a car underframe, a channel shaped center sill, in combination with a truss rod, a truss rod support secured to said center sill, a draft sill secured to said center sill, and a draft lug, truss rod anchor member and striking member all secured to said draft sill.

6. In a car underframe, a channel shaped center sill, in combination with a truss rod, a truss rod support secured to said center sill, a draft sill secured to said center sill, said draft sill being of greater depth than the center sill, and a draft lug, truss rod anchor member and striking member all secured to said draft sill.

7. In a car underframe, a bolster, a center sill extending beyond the bolster, an end sill, and draft sills extending from said end sill to the end portions of said center sill, a truss rod anchor member secured to

- said draft sill, and a truss rod extending above the bolster, through the end sill and secured to said anchor member, a draft lug secured to said draft sill and a T-shaped striking member resting upon and secured to the upper flanges of said draft sill.
8. In a car underframe, a bolster, a center sill extending beyond the bolster, an end sill, and draft sills extending from said end sill to the end portions of said center sill, a T-shaped striking member resting upon and secured to the upper flanges of said draft sill, a truss rod anchor member secured to said draft sill and to said striking member, and a truss rod secured in said anchor member.
9. In a car underframe, a bolster, a center sill extending beyond said bolster, a draft sill having a depth greater than the depth of said center sill, and whose lower portion extends below the horizontal plane of the lower portion of the center sill, and a tie plate secured to the lower portions of the center sill and to the lower portion of the draft sill which extends below the horizontal plane of the lower portion of the center sill.
10. In a car underframe, a center sill, a draft sill lapped past the end of and secured to the center sill, a top flange on said
- draft sill, said flange for a portion of its length being in substantially the same horizontal plane with the top flange of said center sill, and for the remainder of its length being below the horizontal plane of said top flange, a bottom flange on said draft sill, said flange being below the horizontal flange of the lower flange of the center sill.
11. In a car underframe, a center sill, a draft sill lapped past the end of and secured to said center sill, said draft sill being of greater depth than said center sill, a top flange on said draft sill extending toward the center line of the underframe for a portion of its length, and extending in an opposite direction from the center line of the underframe for the remainder of its length.
12. A draft sill of Z section for a portion of its length and of channel section for the remainder of its length.
13. A draft sill of Z section having a channel shaped end portion.

In testimony whereof I affix my signature in presence of two witnesses.

PETER PARKE.
